2 SHEETS—SHEET 2.

UNITED STATES PATENT OFFICE.

FREDERICK WILLIAM CONSTANTINE, OF ST. ANNES-ON-SEA, AND THOMAS GEORGE KAY, OF BOLTON, ENGLAND.

DRAG DEVICE FOR SPINNING MACHINES.

1,414,688.

Specification of Letters Patent.

Patented May 2, 1922.

Application filed June 4, 1920. Serial No. 386,512.

To all whom it may concern:

Be it known that we, FREDERICK WILLIAM CONSTANTINE and THOMAS GEORGE KAY, subjects of the King of Great Britain, and residents, respectively, of 5 Kensington Road, St. Annes-on-Sea, in the county of Lancaster, and 54 Back Cheapside, Bolton, in the same county, England, have invented a certain new and useful Improvement in Drag Devices for Spinning Machines, of which the following description, having reference to the accompanying sheet of drawings, is a specification.

Our invention relates to improvements in spinning, doubling, twisting and like machines used in the production of yarns or threads of fibrous substances and particularly to means for regulating the drag on the spindles in such machines. The class of drag devices to which our invention especially relates is that wherein centrifugally acting rolling devices are mounted on discs fixed upon loosely mounted spindles, and operating in conjunction with weights, as set forth in our patent specification No. 121142. In the said patent specification centrifugal rolling devices are employed which are free to move in any direction either radially or in a rotary path around the spindle in conjunction with which they operate, and we have found that it may be preferable or desirable to employ rolling devices which are constrained to follow a certain path radially when brought into operation and in some cases to be entirely prevented from moving radially, although such rolling devices act in a centrifugal manner. Our present invention therefore consists in the employment of improved devices whereby when these centrifugally acting means are allowed radial movement, guiding devices are made use of to constrain them to follow certain paths. Other means are also employed whereby the rolling devices are free to rotate but are prevented from moving radially relatively to their support. We also employ, in an alternative arrangement, conical parts mounted upon the spindles, or a series of discs of different diameters, whereby they are enabled to pick up or be acted upon by series of weights. Where weights are employed which are gradually brought into action with these rolling devices we employ improved means for operating same, these improved means consisting

of a cam operating in conjunction with rails which are movable vertically and also relatively to each other.

In order that our said invention may be readily understood, we have hereunto appended sheets of drawings illustrative thereof, to which, by figures and letters, reference is made in the following description.

Fig. 1 is a front elevation of a portion of a spinning machine having our improvements applied in connection therewith.

Fig. 2 is a sectional end elevation thereof.

Fig. 3 is a plan of certain of the parts illustrated by Figs. 1 and 2.

Fig. 4 is a sectional elevation of a spindle and its appurtenances showing our improved drag regulator mounted in connection therewith.

Fig. 5 is a plan showing a disc with guiding devices mounted in connection therewith for the centrifugally acting means.

Fig. 6 is a sectional elevation thereof.

Fig. 7 is a plan of a holder for the rolling devices wherein such devices are allowed slight bodily movement away from the spindle in connection with which they operate.

Fig. 8 is a side elevation thereof.

Fig. 9 is a plan showing arms radiating from the spindle and provided with guides or ways for the balls.

Fig. 10 is a plan of a disc formed with a concentric groove for the reception of the balls, which latter, although free to revolve around the spindle, are prevented from radial movement relatively to the spindle.

Fig. 11 is a sectional elevation of said disc.

Fig. 12 is a plan of a holder for a series of balls which confines them to rotative motion only.

Fig. 13 is a side elevation thereof.

Similar letters and figures of reference indicate like parts throughout the several views.

A indicates the framework of the machine, and α a series of loosely mounted spindles, these resting in bearings b^1 in a rail b . On another rail c are lateral bearings a^1 for said spindles α , the two rails b and c being raised and lowered by the lifter motion operating through the usual pokers g , the rail b thus acting as the usual lifter rail. The lifter motion raises and lowers said spindles α within the rotary flyers d mounted on a

rail d^1 and rotated in any appropriate manner at a high rate of speed, the movement of said spindles through said flyers d regulating the winding of the yarn thereon. Or 5 we may traverse the flyers d over the spindles a for the same purpose.

It is well known that at the commencement of the winding of yarns upon the bare spindle or upon thin tubes mounted thereon 10 that very little retardation should be exercised on said spindles at this time, and that more drag should be given thereon as the cops approach completion, while further than this the drag should be altered during 15 each reciprocation of the lifter motion.

We have found that it necessitates the employment of rolling devices to obtain a drag light enough at the commencement of the winding operations and these rolling devices consist of balls x resting upon discs a^2 fixed upon the spindles a . In conjunction with these rolling devices x we may employ weights or covers k which merely rest upon the balls or rolling devices x as shown 20 by Fig. 6, although we preferably employ a series of weights in connection therewith as hereinafter described.

In our former specification above referred to the rolling devices therein described were 30 allowed free movement over the surfaces of the discs upon which they were mounted, however we now find that it may be preferable to confine them in their movement relatively to the spindles a , consequently instead of discs we may employ arms n having channels n^1 for the reception of the balls or rolling devices x , these being capable of occupying central positions in proximity to the spindles a or positions at the end of the 35 grooves or guides n^1 , these latter positions being occupied immediately the rotations of the machine are commenced, thus they act in a centrifugal manner and may in certain cases be employed along with covers k or 40 with the series of weights hereinafter described. In Figs. 7 and 8 we have illustrated a series of balls x which are allowed a slight movement bodily away from the spindles a , such movement being controlled by 45 the particular construction of the carrier o .

In Figs. 12 and 13 we have shown a carrier o^1 for the balls x , which allows them simply to rotate and not move bodily toward and from the spindles b , so that such 55 balls x although acting in a manner centrifugally are not allowed movement which is usually caused by such centrifugal action.

In the device illustrated by Figs. 5 and 6, the radially disposed guiding grooves n^1 are formed in the disc a^2 instead of being made in the arms n as shown by Fig. 9, and they answer the same purpose.

Figs. 10 and 11 show merely a groove a^6 formed in the disc a^2 this allowing the balls 60 x to move freely in a direction concentric

with the spindle a by preventing radial movement.

Intervening between the rails b and c is another rail s which has vertical movement transmitted to it simultaneously with and 70 also relatively to the rails b and c . This rail s carries the weighting devices herein-after described and its movement relatively to the two rails b and c regulates the bringing into action of the weighting devices and 75 the length of time in which they operate. The rail c rests upon the collars g^1 fixed on the pokers g while the rail b is supported by the cross pieces b^2 of the bars b^3 , the latter being connected by the links r with the blocks g^2 on the pokers g , other links r^1 connecting the bars b^3 with the rail c . The bars b^3 have horizontal movement transmitted to them as well as vertical movement, and it is the transmission of this horizontal movement thereto that causes its movement relatively to the rails b and c . This horizontal movement of the bars b^3 is effected by the cam t mounted on a shaft or spindle t^1 rotated by bevel gearing t^2, t^3 through the shaft t^4 , and other bevel gears t^5, t^6 from the wheel t^7 which forms part of the ordinary lifter motion. Said cam t rotates in contact with the cross piece u . Its cam surface w as the rail b is reciprocated vertically causes a 95 differential horizontal movement of the bars b^3 and thus moves the rail s a greater or less distance as is required according to the building of the cops a^5 . In order that too much weight has not to be lifted or moved 100 by the cam t we partially counterbalance the parts moved by the bars b^3 by means of the springs 2 connected to the rail b or to the framework A.

The particular weighting device illustrated by Fig. 4 consists of a sleeve or cup s^2 resting upon a sleeve s^3 upon which screws a collar s^4 resting loosely upon the rail s . Within the sleeve or cup s^2 is another cup s^3 having a flange s^4 at its upper end to retain 110 same in position within said sleeve s^2 . The base s^6 of the cup s^3 rests upon the balls x which latter are contained in the holder o^1 . Resting upon the flanges of the cup s^2 is another weight s^8 which by means of the lateral opening s^7 may be passed over the spindle a . It has a flange s^{10} at its upper end to rest upon the flange of said cup or sleeve s^2 . The rail s as it rises and falls will, on moving to a certain distance allow the cup s^3 to 120 rest upon the balls x to exercise a certain amount of drag upon the spindles a while when it moves a short distance lower it allows the weight s^8 to act, on moving still lower will bring into action the weight of 125 the sleeve s^2 in this manner gradually increasing the drag upon the spindles a . By increasing the number of weights any desired drag may be exercised on said spindles a .

We have only illustrated one form of 130

weighting device, but it will readily be understood that any other alternative form may be made use of which will be brought gradually into action and taken out of action gradually, while varied weights which act at all times on the balls or rolling devices in an equal manner, may be employed.

We preferably arrange for the rolling devices or balls α to contact both with the supports α^2 and the parts which rest upon said rolling devices, although in some cases we may only have said rolling devices extending through one side of their plates or guides as shown by Fig. 7.

Such being the nature and object of our said invention, what we claim is:—

1. In spinning, doubling, twisting and like machines, a spindle, a disc fixed upon said spindle, rolling devices mounted on said disc, means for controlling the movement of said rolling devices and a member resting upon said rolling devices.

2. In spinning, doubling, twisting and like machines, a spindle, a support on said spindle, rolling devices mounted on said support, means for controlling the movement of said rolling devices relatively to said spindle and a member resting on said rolling devices.

3. In spinning, doubling, twisting and like machines, a spindle, a support mounted on said spindle, rolling devices mounted upon said support, means for controlling the

radial movement of said rolling devices and a series of weights operating upon said rolling devices.

4. In spinning, doubling, twisting and like machines, a series of spindles, supports mounted on said spindles, rolling devices mounted on said supports, means for controlling the movement of said rolling devices, weighting devices acting on said rolling devices and means for bringing said weighting devices successively into operation.

5. In spinning, doubling, twisting and like machines, a spindle, a support mounted on said spindle, rolling devices resting upon said support, and means for preventing radial movement of said rolling devices.

6. In spinning, doubling, twisting and like machines, a spindle, a support mounted on said spindle, rolling devices resting on said support and a carrier for said rolling devices whereby said carrier and rolling devices rotate together.

7. In spinning, doubling, twisting and like machines, a series of spindles, supports mounted on said spindles, rolling devices, a plurality of weights capable of exercising pressure upon said rolling devices, a reciprocating rail carrying said series of weights and means for reciprocating said rail.

FREDERICK WILLIAM CONSTANTINE.
THOMAS GEORGE KAY.
